Application June 14, 1955, Serial No. 515,426

Claims priority, application Germany June 16, 1954

6 Claims. (Cl. 315—241)

The use of glow discharges in physical or chemical processes, for example for treating metal objects, meets with the difficulties that frequently the glow discharge changes over into an arc discharge, especially when the discharge is of high current strength, and this has a troublesome effect on the objects to be charged. The possibility of stabilising the glow discharge by the use of suitably high limiting resistances connected in series with the discharge vessel is not practical because the process would then become too uneconomical owing to the high consumption of energy. On the other hand, however, the use of a low ohmic limiting resistance leads, when the discharge changes over to an arc discharge, to a momentary very large current which not only endangers the electric installation but makes an undesired burn mark on the object to be treated.

By means of the invention it is possible to overcome the above-mentioned disadvantages and to maintain a suitable glow discharge of high current strength, i. e., a current intensity exceeding 1 amp and in most instances 10 amps, in continuous operation with a relative low consumption of energy. This result is obtained in that, by means of suitable electric circuit elements, the negative current-voltage characteristic of the arc is used, when the glow discharge changes over, to extinguish the arc immediately. As the circuit element there is used, in accordance with the invention, a condenser which is connected in parallel with the glow discharge path and of which the capacity, taking into account the limiting resistance connected in series with the discharge path, is so selected that, when the glow discharge changes over into an arc discharge, the latter causes the arc discharge to be quickly extinguished by utilising the dropping characteristic of the arc discharge. There may also be provided for the gas discharge vessel an ignition device of a known kind which is so dimensioned and designed that the gas discharge is initiated approximately when the necessary glow discharge voltage is reached, and is therefore, automatically set in operation. The current strength and the gas pressure in the discharge vessel are so adjusted that the glow discharge is operated as far as possible in the range of the abnormal cathode drop.

Further details of the invention are illustrated, by way of example, in the drawing which shows the electric circuit.

In the drawing the discharge vessel is designated by the reference G, the parallel condenser by the reference C, the series limiting resistance by the reference R₁ and the source of current, which is preferably adjustable, by the reference S. The limiting resistance R₁ is so dimensioned that normally a glow discharge is maintained in the discharge vessel G. If now the glow discharge changes over into an arc discharge, then the condenser C is discharged to the voltage drop at the discharge path. Consequently, there flows through the limiting resistance R₁ for a very short time a considerably stronger current than can be delivered by the source of current S alone. This causes a further heavy drop in the operating voltage. However,

2

the current which is now supplied only through the limiting voltage R₁ is no longer sufficient for the low operating voltage, so that the discharge is extinguished. This effect is still further promoted by the condenser C which is only charged again when the voltage increases.

It has been found by experiment that the duration for which the arc burns is, in general, so short that no burn mark is produced on the cathode on the discharge vessel. Further the occurrence of a burn mark can be avoided with certainty by connecting, in the circuit which contains the gas discharge path and is in parallel with the condenser C, a resistance R₂ which is considerably smaller than the limiting resistance R₁, which resistance R₂ receives the energy of the condenser corresponding to the high current strength.

In order to produce a stable glow discharge of 50 amperes, the individual circuit elements may be dimensioned for example as follows:

$$R_1=7 \text{ ohms}, R_2=0.02 \text{ ohms}, C=40 \mu\text{f}.$$

In order to maintain the loss of energy which occurs when operating glow discharge as small as possible, it is advantageous to keep the limiting resistance connected in series with the discharge path as small as possible. In the above-mentioned circuit, however, the size of the limiting resistance has a lower limit owing to its co-operation with the condenser.

According to further features of the invention the above-mentioned limitation is avoided in that there is connected in series with the limiting resistance an additional choke L which, when the glow discharge changes to an arc discharge, limits the momentary current which flows to a considerably greater extent than an ohmic resistance. It is then advantageous to dimension the choke L, the limiting resistance R₁ and the condenser C in such a way that a damped oscillating circuit is formed, the first voltage maximum of which is so high that the glow discharge is again initiated without external ignition.

The limitation of the current flowing when the glow discharge changes over to an arc discharge when the choke L is present is no longer effected solely by the limiting resistance R₁ but to a considerably stronger extent at the moment of change-over owing to the inductance L. The ignition device Z, for again initiating the glow discharge after being extinguished can be omitted, if as above-mentioned, R, L and C are properly dimensioned. The resistance R₂ illustrated in the drawing is considerably smaller than the resistance R₁, and for this purpose the ohmic resistance of the leads is generally sufficient. The resistance R₂ serves the purpose of taking considerable part of the energy of the condenser C when the glow discharge changes over to an arc discharge.

For the continuous operation of a glow discharge of 200 amperes the circuit elements may, for example, be dimensioned as follows:

$$R_1=1 \text{ ohm}; C=100 \mu\text{f};$$

$$L=5 \text{ microhenries and } R_2=0.0002 \text{ ohms}$$

The operation of the circuit according to the invention will now be explained in more detail.

Experimental recordings indicate that the breakdown of the glow discharge to an arc discharge initiates an oscillation of approximately sinusoidal character, causing the voltage across the capacitor C to decrease to negative values. Extinction of the arc occurs almost simultaneously with the negative peak of the voltage across the capacitor C. This is readily understood since at this particular instant the current in the vessel would have to change sign. With the current path through the vessel interrupted, the circuit reduces to a simple RC-network. The capacitor voltage now increases exponentially until a positive voltage value across the vessel is reached

which is sufficiently high to reinstate the glow discharge.

As a matter of interest, the time between breakdown and extinction was found to amount to something between 10^{-6} and 10^{-5} seconds. This is by far less than an arc discharge requires to build up completely and to do any harm. Visually, the breakdown appears in the form of an extremely short and rather dim flash. No real arc is observed.

Considering that an electric oscillation requires the presence of inductance as well as capacitance, there is good reason to believe that the inductance inherent in the mesh comprising vessel G, capacitor C and the leads connecting the two takes an active part in the process. Quantitative analysis shows that the effective inductance amounts to just a few microhenries, an amount always present in a circuit of the physical size involved here. Hence it is unnecessary to provide an inductance in the mesh referred to by inserting a coil. In fact, this was never done.

We claim:

1. In an apparatus for surface-treating metal objects or the like in a vacuum vessel in the presence of a continuously burning glow discharge, in combination: a glow discharge vessel adapted to operate at currents exceeding 1 amp.; a pair of electrodes spacedly arranged inside said vessel; a source of electric energy; a first resistor and a second resistor; said electrodes, said electric energy source and said first resistor being connected in series; and a capacitor connected in parallel to said electrodes and said second resistor; the resistance of said first resistor being less than the resistance across said electrodes and said second resistor, when a glow discharge is present in said vessel; whereby an arc discharge resulting from a breakdown of a glow discharge in said glow discharge vessel is extinguished and said glow discharge reinstated.

2. In an apparatus as claimed in claim 1, a choke connected in series with said resistor.

3. In an apparatus as claimed in claim 2, the lower limit of the product of the resistance of said resistor and

the capacitance of said capacitor being of the order of 10^{-4} seconds.

4. In an apparatus as claimed in claim 3, said glow discharge vessel being adapted to operate at a current of the order of 50 amps., said resistor having a resistance of the order of 7 ohms, and said capacitor having a capacitance of the order of 40 microfarads.

5. In an apparatus as claimed in claim 3, said glow discharge vessel being adapted to operate at a current of the order of 200 amperes, said resistor having a resistance of the order of 1 ohm, and said capacitor having a capacitance of the order of 100 microfarads.

6. In an apparatus for surface-treating metal objects or the like in a vacuum vessel in the presence of a continuously burning glow discharge, in combination a glow discharge vessel adapted to operate at currents exceeding 1 ampere; a pair of electrodes spacedly arranged inside said vessel; a source of electric energy; a first resistor; a second resistor, said electrodes, said second resistor, said first resistor and said source of electrical energy being connected in series; and a capacitor connected in parallel to said electrodes and said second resistor, the resistance of said first resistor being less than the resistance across said electrodes and the second resistor, whereby an arc discharge resulting from a breakdown of a glow discharge in said glow discharge vessel is extinguished and said glow discharge reinstated.
